MEANS FOR SUPPORTING PIT-FURNACE COVERS

William A. Morton, Mount Lebanon, Pa., assignor to The Amsler-Morton Company, Pittsburgh, Pa., a corporation of Pennsylvania

Application June 4, 1943, Serial No. 489,624

8 Claims. (Cl. 266—31)

This invention relates to pit furnaces and, in particular, to means for supporting the cover thereof when in position on the furnace.

Covers for pit furnaces, such as soaking pits for the heating of steel ingots, as previously designed and constructed, have been supported, when placed in position over the pit, by the margins of the walls thereof. Pit-furnace covers are usually very large and quite heavy and are frequently removed and replaced. There is thus considerable likelihood, with the construction previously employed, of damaging the margins of the pit walls, unless extreme care is exercised in "spotting" the cover before lowering it. This likelihood is materially increased by the presence of the conventional sealing flange depending from the bottom of the cover, extending continuously around the edges thereof and adapted to enter a sealing channel formed in the top of the pit walls and filled with granular material such as sand. It will be readily appreciated that the sealing flange may seriously damage the pit walls unless the cover is accurately centered before being lowered into its final position of rest on top of the walls.

I have invented a novel means for supporting the cover of a pit furnace which overcomes the aforementioned objections to the construction previously used. I provide members projecting outwardly from the cover, preferably the principal structural members of the fabricated frame customarily provided to carry the refractory lining which serves as the actual closure for the pit. I also provide supports so positioned outside the furnace walls as to be engaged by the projecting members of the cover frame as it is lowered into position. These supports are carried on a structure outside of and independent of the walls of the pit or their binding, i. e., the enclosure fabricated from plate and structural members within which the brickwork composing the furnace walls is laid up. The projecting members of the cover frame and the supports engaged thereby are provided with coating surfaces of such shape as to center the cover automatically as it is lowered into position, and thus assure proper alignment of the sealing flange on the cover with the sealing channel in the top of the furnace walls.

A complete understanding of the invention may be gained from a consideration of the following detailed description and the accompanying drawings illustrating a preferred embodiment and a modification. In the drawings,

Figure 1 is a partial side elevation of a pit

furnace with its cover embodying my invention, positioned thereon, showing also a known form of crane for raising and supporting the cover;

Figure 2 is a partial plan view, showing one corner of the cover and crane;

Figure 3 is a partial section taken substantially along the plane of line III—III of Figure 2 showing the crane and cover in elevation;

Figure 4 is a partial elevation, to enlarged scale, showing the cooperation between the projecting members of the cover and the supports engaged thereby; and

Figure 5 is a view similar to Figure 3 showing a modification.

Referring now in detail to the drawings and, for the present, to Figures 1 through 4, the upper portions of the walls of a pit furnace are indicated at 10. These walls are laid up from insulating and refractory brick within a binding 11 fabricated from structural members and plates in the known manner. A sealing channel 12 is formed in the top of the walls and extends continuously around the edge of the pit.

A cover for the top of the pit is indicated at 13. It is fabricated from structural members including principal longitudinal beams 14 and transverse beams 15, as well as the additional auxiliary members necessary to provide a rigid frame for supporting a refractory lining which constitutes the actual closure overlying the top of the pit. The lining is composed of refractory brick suspended beneath the cover within a marginal row of castings 16 secured below the longitudinal and transverse frame members. A sealing flange 16a extending around the bottom of the cover is secured to the castings 16.

As clearly shown in Figures 2 and 3, the ends of the longitudinal beams 14 project outwardly beyond the cover as defined by the beams 15. Shoes 17 are secured to the bottoms of the projecting ends of the beams 14 and are adapted to engage chairs or bearing members 18. The members 18 include a base 19 and a bearing block 20 of inverted V-shape. The members 18 are secured to beams 21 outside the furnace walls. The beams 21 are supported on columns (not shown) extending upwardly from a suitable foundation. The shoes 17 have a V-shaped notch in their bottom surface as shown in Figure 4 forming in shape to the blocks 20 of the members 18. By virtue of the shape of the coating surfaces of the shoes and blocks, the cover 13 centers itself relative to the furnace walls as it is lowered onto the supporting members and thus insures that the sealing flange 16a properly

enters the sealing channel 12. Since the shoes 11 and blocks 20 will correct a considerable misalignment of the cover with respect to the pit, it is unnecessary for the cover to be "spotted" with a high degree of accuracy. This results in a substantial saving of time in placing the cover over the pit.

For the sake of completeness, I have shown a known form of crane 22 for lifting and transporting the cover 13. The details of the crane 10 are disclosed in Spencer Patent No. 2,287,645 and a complete description thereof is thus unnecessary. Briefly, the crane includes a frame composed of longitudinal members 23 and transverse members 24. Wheel castings 23' secured to the longitudinal frame members are provided with bearings in which are journaled wheels 25 traveling along rails 26 on opposite sides of the pit. A motor 27 drives the wheels at one end of the crane through a reducer 28 and gearing 29. Cover-lifting mechanism includes bell cranks 30 pivoted on fixed fulcrums and provided with links 31 from which the cover is suspended. A crank shaft 32 has connecting rods 33 pivoted to the bell cranks whereby the cover 13 is lifted on rotation of the shaft 32 by a motor 34 working through a reducer 35. Instead of the crane shown, a crane of the detachable type as shown in Spencer Patent No. 2,232,281, may be used.

Modified forms of shoes and bearing blocks are shown in Figure 5. Blocks 36 in the form of castings are adapted to receive rollers 37, the rollers being disposed with their axes in inclined planes intersecting at the median vertical plane through the blocks. The blocks 36 rest on beams 21' corresponding to the beams 21. Shoes 38 have V-shaped bottom faces adapted to cooperate with the rollers 37 and thereby serve to center the cover in the same manner as the shoes 17 and blocks 20. Figure 5 shows how the shoes and blocks may be disposed to center the cover both longitudinally and transversely. For this purpose, alternate sets of shoes and blocks progressing around the periphery of the cover and furnace are disposed at right angles. For example, the shoe and block at the left in Figure 5 with a shoe and block similarly arranged at the diagonally opposite corner of the cover serve to center it longitudinally. Similarly, the shoe and block shown at the right in Figure 5, with the diagonally opposite shoe and block likewise arranged, serve to center the cover transversely. It will be apparent that because of the considerable width of the blocks 37 and shoes 38, even a large error in "spotting" the cover over the pit will be corrected as the cover descends to its final resting position.

It will be readily understood from the foregoing description that my invention is characterized by important advantages over the previous practice in the construction of covers for pit furnaces in that I avoid the likelihood of damage to the margins of the pit walls as a result of placing the cover directly thereon. By providing special supporting members with their own structural framework independent of the furnace binding, I save the walls from the destructive effect of lowering the heavy cover repeatedly thereon. I also insure proper positioning of the sealing flange relative to the sealing channel when the cover reaches final position, even though not precisely aligned prior to lowering.

Although I have illustrated and described herein but a preferred embodiment of the invention and a modification, it will be recognized that the principles of the invention disclosed may be embodied in forms other than those shown without departing from the scope of the following claims.

I claim:

1. A cover for a pit furnace comprising a frame fabricated from structural members provided with a refractory lining and adapted to be lowered over the furnace, chairs on opposite sides of the furnace, and supports for the chairs independent of the furnace, certain of said members extending outwardly of the cover and having portions adapted to engage said chairs.
2. A cover for a pit furnace comprising a frame including longitudinal and transverse principal members provided with a refractory lining and adapted to be lowered into position over the furnace, cover supports on opposite sides of the furnace, and means independent of the furnace on which said supports are mounted, certain of said members projecting outwardly from the cover and having portions adapted to engage said supports.
3. A cover for a pit furnace comprising a frame including marginal longitudinal and transverse principal members, adapted to be lowered over the furnace, and cover supports outside the furnace, certain of said members extending beyond the cover proper and being adapted to engage said supports as the cover reaches final position.
4. The apparatus defined by claim 3 characterized by means independent of the furnace walls for carrying said supports.
5. A cover for a pit furnace comprising a frame fabricated from structural members provided with a refractory lining and adapted to be lowered over the furnace, and bearing members on opposite sides of the furnace for supporting the cover, certain of said frame members extending outwardly from the cover and having shoes adapted to engage said bearing members.
6. The apparatus defined by claim 5 characterized by said bearing members and shoes being of V-shape.
7. A cover for a pit furnace comprising a frame fabricated from structural members provided with a refractory lining and adapted to be lowered over the furnace, and bearing members positioned outwardly of the furnace walls adapted to support the cover, some of the frame members extending outwardly of the cover and being adapted to engage said bearing members as the cover is lowered over the furnace.
8. A cover for a pit furnace comprising a frame fabricated from structural members and provided with a refractory lining, sealing means on the cover adapted to cooperate with sealing means on the furnace, and bearing members on opposite sides of the furnace for supporting the cover, certain of the frame members extending outwardly from the cover adapted to engage said bearing members, the meeting surfaces of said bearing members and outwardly extending frame members being shaped to guide the cover so that the sealing means thereon will register with the sealing means on the furnace as the cover is lowered onto said bearing members.

WILLIAM A. MORTON.
